United States Patent Office.

GEORGE A. PRIDHAM, OF NEWARK, NEW JERSEY.

Letters Patent No. 73,926, dated January 28, 1868.

IMPROVED SPOOL-STAND.

The Schedule referred to in these Letters Patent and making part of the same.

TO ALL WHOM IT MAY CONCERN:

Be it known that I, GEORGE A. PRIDHAM, of Newark, in the county of Essex, and in the State of New Jersey, have invented certain new and useful Improvements in Device for Holding Spools; and do hereby declare that the following is a full, clear, and exact description thereof, reference being had to the accompanying drawings, and to the letters of reference marked thereon.

In the annexed drawings, making part of this specification, A represents a long, narrow box, made of metal, or other suitable material, having only a bottom and two sides. The sides may be scalloped, or ornamented in any desirable manner, and sufficiently wide apart to receive spools of cotton or silk between them. B represents a bar, with a series of arms or pins, C C C', formed or secured upon one side of it. These arms or pins act as axes for the spools, and pass through the box, having bearings in its sides. e e represent the series of holes in the sides of the box to receive the pins C C'. The centre pin C' is provided, on one end, with a screw-thread. When the bar is supporting spools upon its arms or pins, as seen in fig. 1, a nut is passed over the threaded end of pin C', to secure the bar to the box, and in position.

By the use of this box and bar B, spools are conveniently held, and may be readily changed or shifted when it is desirable.

What I claim is, the box A, in combination with the bar B, with its arms C C C', and used as and for the purpose set forth.

In testimony that I claim the foregoing, I have hereunto set my hand and seal, this 4th day of November, 1867.
